UNITED STATES PATENT OFFICE.

ELIZABETH FALCONER, OF LOUISVILLE, KENTUCKY.

SHOE-LACING.

No. 797,052.

Specification of Letters Patent.

Patented Aug. 15, 1905.

Application filed October 8, 1904. Serial No. 227,701.

To all whom it may concern:

Be it known that I, ELIZABETH FALCONER, a citizen of the United States, residing at Louisville, in the county of Jefferson and State of Kentucky, have invented certain new and useful Improvements in Shoe-Lacings; and I do hereby declare the following to be a full, clear, and exact description of the invention, such as will enable others skilled in the art to which it appertains to make and use the same.

My invention relates to a method or system of lacing shoes; and my object is to obviate the annoyance of the tangling loops and ends and also dispense with the necessity of daily lacing and unlacing the shoe, thereby providing a system of lacing which requires no attention except when a new lace is needed to replace a lace which has become worn and useless.

My invention will be found adapted and suitable for all kinds of laced shoes, the means employed in adjusting the lace being substantially the same for high and low shoes, the length of the lace being varied, as will be obvious, to conform to the number of eyelets in the shoe.

My invention will be hereinafter fully set forth, and pointed out in the claim and illustrated in the accompanying drawing, wherein I have shown a shoe of the usual construction.

By reference to the drawing it will be observed that I have placed two eyelets side by side in the upper end of the tongue of the shoe, and I then take the shoe in the left hand and the left end of the lace in the right hand, pushing it through to eyelet 1 to the back of the tongue. I then push it through eyelet 2 to the front, then pass down to eyelet 3 at the vamp of the shoe, bringing it out at the front and across to eyelet 4 on the outside and through to eyelet 5 on the inside, all with that side of the lace, then take the other end of the lace and bring it up through eyelet 6 to the front. I then lace the shoe in any special way which may be desired between the upper and lower pairs of eyelets—as, for instance, the string may be crossed or arranged to extend transversely across the face of the shoe from one eyelet to the opposite eyelet, all of this being left to the preference of the wearer.

My system of lacing may be applied to shoes in stock at no extra expense to the manufacturer. It can also be applied to corsets, leggings, gloves, and the like.

To put on the shoe, the lace passing through the eyelets in the shoe proper is loosened sufficiently to admit the foot, and after the shoe is on and adjusted the lace is again drawn taut in the eyelets, beginning at the top and passing to the bottom of the series of eyelets. You then slip the finger in at the back of the tongue and pull up the slack first on one side and then on the other and then fold up the lace and tuck it inside the leg of the shoe. The lace will not become undone until you release it. To take off the shoe, grasp the lace at the vamp and pull it down, then slacken up without disturbing the lace as fixed in the shoe.

It will thus be seen that I have provided a simple though reliably-efficient form of lacing system by means of which a shoe of any character may be very tightly laced and unlaced and that when secured in a laced condition the shoe will present a very neat and attractive appearance. It is further obvious that my system of lacing may be applied, as aforesaid, to the lacing of corsets, gloves, and the like, and believing that the advantages, &c., have thus been made fully apparent further description is deemed unnecessary.

What I claim as new, and desire to secure by Letters Patent, is—

The combination with a shoe having a series of eyelets therein and a tongue secured at one end within the shoe and having eyelets in its free end; of a lace extending through the eyelets in the tongue and forming an intermediate loop arranged longitudinally upon the tongue, the free ends of the lace being interlaced in the eyelets of the shoe successively from one end to the other of the series of eyelets, whereby the lace may be loosened or tightened by manipulating the ends and loop thereof.

In testimony whereof I have signed my name to this specification in the presence of two subscribing witnesses.

ELIZABETH FALCONER.
